CLAIM

The ornamental design for a belt mounted eyeglass case or the like, substantially as shown and described.

DESCRIPTION

FIG. 1 is a top plan view of a belt mounted eyeglass case or the like embodying my new design;

FIG. 2 is a front elevational view thereof;

FIG. 3 is a right side elevational view thereof;

FIG. 4 is a rear elevational view thereof; and

FIG. 5 is a bottom plan view thereof.

The dashed lines on the eyeglass case represent stitching.
